UNITED STATES PATENT OFFICE

2,371,039

TWO-WAY LACE CURTAIN

Lester Fischel, New York, N. Y., assignor to
Patchogue-Plymouth Mills Corporation, New
York, N. Y., a corporation of New York

Application September 5, 1942, Serial No. 457,419

7 Claims. (Cl. 160—385)

This invention relates to a two-way lace curtain, particularly to a two-way Nottingham lace curtain. It is especially applicable to a two-way Nottingham lace curtain either of the ready-to-hang or of the adjustable ready-to-hang type, such as are disclosed generally in my prior Patent U. S. 2,149,011, granted February 28, 1939.

Nottingham lace curtains are commonly woven in several different standard lengths and in different widths, thus being designed, when finished, to fit windows of different sizes. Lace curtains are also woven in different widths to produce pair goods and panels. Generally speaking, lace curtain goods having a loom width not exceeding 40 inches, are classed as pair goods, and lace curtain goods exceeding 40 inches loom width are classed as panels. The width of a curtain is an important factor in the cost of production and therefore in the selling price, so that ordinarily two panels are more expensive than a pair of curtains of the same style, quality and length. A panel curtain is not readily adaptable for subdivision into pair goods, because if a panel curtain were thus subdivided the lace fabric would unravel, unless the lace fabric were of such a character that it could be effectively and promptly hemmed; and a panel curtain which produces the most effective eye-appearance when draped in panel form completely across a window of appropriate width, is less effective in eye-appearance when draped across only one-half of the width of the said window to form one-half of a "pair" of curtains composed of two matched full size panel curtains, because when two panels are thus draped full size, the window presents an overcurtained appearance.

The object of this invention is a two-way Nottingham lace curtain, which is normally ready-to-hang in one way in panel form at a window of suitable width, but which can be quickly separated without impairing the fabric, the weave, the pattern, or the finish of the goods, into a second way, wherein said former panel now constitutes two matching curtains, each of narrower or half-panel width, completely finished and ready-to-hang as a pair of curtains, at the same window as before.

Another object is a ready-to-hang curtain which may be converted from panel to pair goods form, without any additional cost or substantial effort, on the housewife's part.

Another object is a curtain which is so woven that when cut lengthwise to separate it into sections forms two or more finished matched cur-

tains, which are ready for hanging immediately as pair goods.

Other objects will appear from the detailed description.

5 In accordance with this invention the curtain is woven on the loom, preferably in the form of a ready-to-hang panel curtain, consisting of at least two sub-panels, united together throughout the length of the warp by at least one draw-thread, which may be a spool thread, so that by withdrawing the draw-thread the said panel is instantly subdivided into at least two matched sub-panels which can be grouped in pairs to form fully finished ready-to-hang pair goods.

15 In the drawings comprising three sheets of eight (8) figures numbered Figures 1 to 8 inclusive:

Fig. 1 is a front view of an adjustable ready-to-hang Nottingham lace curtain woven in the form of a panel curtain, showing enough of the weave, and pattern of the finished curtain fabric, to disclose my invention generally.

Fig. 2 is an end view of the curtain of Fig. 1.

Fig. 3 is a front view of a fragment of the lace fabric of the curtain of Fig. 1 enlarged to more clearly illustrate the draw-thread before it is removed.

Fig. 4 is a front view of the fragment of lace fabric of Fig. 2, with the draw-thread partly removed to partially separate the lace fabric into two distinct but matched (left and right) sections.

Fig. 5 is a detailed view of the weave construction.

35 Fig. 6 is a front view of a central fragment of the lace curtain of Fig. 1 adjustably threaded in panel form upon a suspension rod.

Fig. 7 is a front view of the central fragment of the panel curtain of Fig. 6, separated into two matched (left and right) half-panels and threaded upon a suspension rod to illustrate intermediate length adjustment as pair goods; and

Fig. 8 is a front view of a fragment of a lace curtain embodying my invention in a panel curtain having a hemmed passageway.

Like reference characters designate corresponding parts throughout the several figures of the drawings.

Referring first to Fig. 1, the lace panel curtain 50 10 is woven in one piece. It consists of two matching sub-panels 11 and 12. Each sub-panel 11 and 12, has a lace body portion 21, which is preferably finished off in any suitable manner, as with a lace heading 20 which merges at 19 with 55 the upper end of the body portion 21 of each

sub-panel. Lace heading 20 may be constructed so as to include one or more rod engaging passageways, to make the curtain of the ready-to-hang type. The passageway may consist of a row of horizontally spaced slots 18, woven in the lace heading 20 as a part of the pattern, said slots being elongated and large enough to be threadable upon the conventional curtain rod 30 (Fig. 6). The side edges of curtain 10 (Fig. 1) are finished off with a non-ravelling edge 36 of any selected type. The curtain 10 may be of any preferred weave, such as double action, combination goods, or filet. The pattern or design woven in the sub-panel 12 is a reverse replica of the pattern or design woven in the sub-panel 11, so that the two halves complement one another in all respects.

Groups of warp threads (Fig. 5) positioned upon opposite sides of the longitudinal median line of the curtain 10, are clothed to form two separate and distinct spaced bands of clothing defining two spaced but parallel selvage edges 23 and 25 (Figs. 1 and 3), which are secured together to form one lace curtain, as by means of a spool thread 24. Draw thread 24 may be woven as a spool thread. It is anchored at spaced intervals to the spaced warp threads 37 and 38 (Fig. 5), by means of bobbin threads 39 and 40, which also serve to anchor the clothing which forms the selvage edges 23 and 25. The thread 24 traverses the adjacent spaced selvage edges 23 and 25 of the sub-panels 11 and 12 longitudinally, being secured at spaced intervals to the warp threads 37 and 38 of said selvage edges 23 and 25 (Fig. 5), in any suitable manner which permits the thread 24 to be drawn out by hand (Fig. 4), so as to separate lace curtain 10 without injury to the lace fabric into two completely finished and distinct narrower curtains or half-panels 11 and 12, of complementary pattern. By this simple withdrawal operation of the draw thread 24, the panel curtain 10 and its balanced pattern (Fig. 1), is for all practical purposes, converted without injury, into a finished pair of curtains consisting of two (left and right) half-panels, each half-panel being substantially one-half the width of the original panel curtain 10 from which it was separated, the pattern in the right half-panel being a reverse replica of the pattern in the left-half panel, the two half-panel (or half-pair) curtains being identical in all other respects, and being completely finished and ready-to-hang from a curtain rod 30 (Fig. 7), as a pair of curtains. The spool thread 24 is woven into the selvage edges 23 and 25 in such a manner that it can be broken and drawn out by hand, without unravelling or otherwise damaging any portion of the lace fabric thereafter remaining, unbalancing the pattern, or impairing the finished appearance of the lacework. The only material change effected by withdrawing thread 24 being the physical separation of the panel curtain 10 into two narrower or half-panel curtains, ready-to-hang upon a curtain rod 30 (Fig. 7) as pair goods.

My invention may therefore be quite properly referred to as a two-way curtain, because while in the form in which it is made and sold it can be hung as a panel curtain, it can be taken down, and by the simple operation of withdrawing the thread 24, the housewife may change panel curtain 10 into two matching narrower or half-panel curtains, which, unless soiled, are ready to be hung immediately at the same window as before.

As the narrow curtains match, or have complementary patterns, they may be hung as pair goods or pairs of curtains, without any indication that they were formerly adjoining sections of a panel curtain.

While the invention has been described as applied to a ready-to-hang curtain, it may be applied with equal ease to an adjustable ready-to-hang curtain, such as is disclosed in Figs. 1 to 7. When the invention is embodied in a ready-to-hang curtain of the adjustable type, two or more rows of horizontally spaced slots 18, 16, 14, are woven in the lace heading 20. To compensate for shrinkage which takes place in the lace curtain 10 when it is washed and laundered for the first time, the slots, 18, 16, 14, may be spaced on vertical centers, such that the distance between the adjacent rows of slots (18, 16, 14) when measured vertically between centers, substantially corresponds to the amount of shrinkage which takes place when the curtain is first washed and laundered by the housewife.

If it is desired to compensate for the cumulative effect of shrinkage throughout the useful life of the curtain, due to repeated washing and laundering, the lace heading 20 may be woven sufficiently long to include one or more additional rows of slots 14 (Fig. 1) woven therein, so that the lace curtain 10 will be adjustable to at least three different lengths, designated for convenience minimum length, intermediate length, and maximum length, corresponding to suspension from the lowermost row of slots 18, the intermediate row of slots 16, and the uppermost row of slots 14, respectively. When the curtain is adjusted to intermediate or to minimum length, the heading is folded over midway between the rows of slots 14, 16, and 18, either once, or twice, as the case may be, to bring each slot 14 into registry with the corresponding slot 16 (and 18), to form a common slotted passageway through which a curtain rod may be threaded thus locking the folded heading 20 against change of curtain length, while simultaneously producing an ornamental heading for the curtain above and below the curtain rod.

Rows of openwork 15 and 17, may be woven in the lace heading 20, said rows of openwork being symmetrically disposed on opposite sides of the transverse median line between the rows of slots 14—16, 16—18, so that when the curtain is folded over (and over) along said median line(s) as the line(s) of fold, the two halves of the folded openwork will register optically, and form an indented edge band for the heading either above, or above and below the curtain rod. The upper extremity of the curtain may be finished off with a hemmed edge 13, said hem being securely held by a line of stitches 28, and the lower extremity 41 of the curtain may similarly be finished off by hemming at 42. The first and last two slots 22—22, 26—26, 27—27, on each row are spaced relatively close together and in close proximity to the edges and prospective edges of the curtain. By this arrangement the edges of the curtain closely hug the curtain rod 30.

The heading 20 of the adjustable ready-to-hang panel curtain 10 of Fig. 1, may be folded over and over, to bring the several rows of slots in the triple ply formed fold into co-operative registry, and the slots are then threaded upon curtain rod 30, and the panel is draped substantially as shown in Fig. 6.

Removing the draw-thread 24 (Fig. 4), sub-

divides panel curtain 10 into two matching finished adjustable ready-to-hang curtains (see Fig. 7). The headings 20 may be folded over and over as before to form triple, ply folds, and the half-panels 11 and 12, may be threaded upon curtain rod 30, and draped at the window as a pair of curtains.

After the curtain is washed and laundered for the first time it will be several inches shorter than before. To compensate for this shrinkage, the heading 20 may be folded over to form a double ply fold, and threaded upon the curtain rod 30 with the lowermost row of slots 18 exposed (Fig. 7). After repeated washings the curtain will shrink still further, and to compensate for this additional shrinkage the curtain may be threaded upon the curtain rod 30 from the uppermost row of slots 14 only.

The invention may likewise be applied (Fig. 8) to a panel curtain 31 having a hemmed rod-engaging passageway 32, secured in place with lines of hemstitching 29 and 33. The curtain rod 30 is threaded through the passageway 32. To subdivide panel curtain 31 into two sub-panels 34 and 35, the draw-thread 24 is withdrawn, to form two half-curtains 34 and 35. The groups of warp threads upon opposite sides of draw-thread 24, are clothed to form two parallel spaced bands of clothing defining two separate selvages, which become the inner selvage edges of the two half-curtains 34 and 35 (Fig. 8) after draw-thread 24 is withdrawn.

The spaced manner of weaving the draw thread 24, leaves the central space between warp threads 37 and 38 relatively open throughout the length of the curtain 10 (Fig. 1), so that when the curtain 10 is hung in panel form upon curtain rod 30 (Fig. 6), the heavily clothed edges 23 and 25, with the relatively un-clothed space in between gives the panel curtain 10 the eye-appearance of a pair of curtains with their adjacent edges drawn close together.

What is claimed is:

1. As a new article of manufacture, a two-in-one lace curtain, said curtain containing a plurality of pre-fabricated sub-sections of lesser width than said article, said sub-sections having their adjacent side edges woven parallel to the warp and in spaced relation to each other, each of said adjacent side edges including a band of clothing forming a part of its sub-section pattern, said sub-sections being complementary and their patterns in conjunction forming one balanced whole, a removable draw-thread woven between adjacent sub-sections of the fabric and secured in said bands of clothing at spaced intervals to unite said sub-sections into a panel curtain, said draw-thread simulating a part of the pattern of said panel, said article being convertible by the removal of said draw-thread, without injury to, or further wastage of, the fabric, from a panel, into a matched pair of curtains, and said bands of clothing thereupon constituting non-ravelling selvage edges for said pair of curtains.

2. A two-in-one lace curtain normally constituting a panel curtain, said panel having a body portion and a heading woven in one piece, a rod-engaging passageway formed in said heading to make said curtain ready to hang in panel form, said panel as fabricated consisting of a plurality of adjoining blanks, said blanks being readily convertible into narrower, but finished, matched, and complementary, ready-to-hang curtains, the pattern of each blank being a reverse replica of one other blank, a band of clothing woven along

the adjoining edges of the body portions of said blanks, a removable draw-thread woven between adjacent blanks and secured to the warp threads thereof at spaced intervals to assemble said blanks as one article, the patterns of said blanks in conjunction, and said draw-thread, forming one balanced whole, said ready-to-hang panel being convertible by the removal of said draw-thread without injury to, or further wastage of, the fabric, into a matched pair of ready-to-hang curtains, and the bands of clothing constituting non-ravelling selvage edges therefor.

3. A two-in-one lace curtain having non-ravelling finished edges, a body portion and a heading woven in one piece, a row of slots formed in the heading, said slots being threadable upon a curtain rod to drape said curtain as a panel, said body and said heading consisting of a plurality of adjoined blanks, each blank being readily convertible into a relatively narrow ready-to-hang half-pair curtain, the pattern of one blank being a reverse replica of an adjoining blank, a band of clothing woven along the adjoining edges of each blank, a removable draw-thread woven between adjoining blanks and secured to the warp threads thereof at spaced intervals to unite said blanks into one ready-to-hang panel, the patterns of said blanks in conjunction forming one balanced whole, said draw-thread simulating a part of the panel pattern, said blanks being convertible by the removal of said draw-thread, without injury to, or wastage of, any of the fabric thereafter remaining, into the complementary halves of a finished, matched pair of ready-to-hang curtains with the bands of clothing forming certain non-ravelling selvage edges therefor.

4. A two-in-one lace curtain of the class described having a body portion and a heading woven in one piece, said heading including a hem-finished-rod-pocket to make said curtain ready to hang as a panel, all of the edges being finished to prevent unravelling, said panel containing a plurality of blanks readily convertible into an equal number of relatively narrow ready-to-hang curtains, the pattern of one blank being reversed relative to that of another, a band of clothing woven along the adjoining edges of each blank, a removable draw-thread extending between adjoining blanks, other threads for securing said draw-thread to the warp to unite said blanks into one manufactured article, the patterns of the united blanks in conjunction forming one balanced whole, said draw-thread simulating a part of and completing the panel pattern, each blank being convertible by the removal of its draw-thread, without injury to, or wastage of, any of the fabric thereafter remaining, into one-half of a finished, matched pair of ready-to-hang curtains, and said bands of clothing constituting certain non-ravelling selvage edges therefor.

5. A two-in-one adjustable lace curtain of the class described having a body portion and a heading woven in one piece, all of the edges thereof being finished to prevent unravelling, a plurality of rows of slots woven in the heading, one row of slots being woven adjacent the line of merger of the body and the heading, and another adjacent the upper extremity of the heading, said rows of slots being variously threadable upon a curtain rod to make said curtain ready to hang as a panel and adjustable to different lengths, said panel containing two blanks readily convertible into a pair of ready-to-hang adjustable curtains, the pattern of one blank being a reverse

replica of that of the other blank, a band of clothing woven along the adjoining edges of the blanks, a removable draw-thread extending from one blank to the other, other threads for securing said draw-thread to the warp to unite said blanks into one ready-to-hang adjustable curtain, the patterns of the blanks when united forming one balanced whole, said draw-thread simulating a part of and completing the panel pattern, said draw-thread, being manually removable without injury to, or wastage of, any of the fabric thereafter remaining, to convert said blanks into a finished, matched pair of ready-to-hang adjustable curtains of complementary pattern, and said bands of clothing constituting certain non-ravelling selvage edges of said matched pair.

6. A two-in-one lace curtain normally constituting a panel curtain, said panel having a body portion and a heading woven in one piece with non-ravelling finished edges, a rod-engaging passageway formed in said heading to make said curtain ready-to-hang in panel form, said panel as thus fabricated being a completely finished article consisting of two adjoining blanks, the pattern of one of said blanks being a reverse replica of the other blank, a removable draw-thread woven between said blanks and secured to the warp threads thereof at spaced intervals to complete the ready-to-hang panel curtain, said ready-to-hang panel curtain being convertible by merely removing said draw-thread without injury to, or further wastage of, the fabric, into a matched pair of ready-to-hang curtains

with all of their edges finished to prevent unravelling thereof.

7. As a new article of manufacture, a lace panel curtain, said panel curtain having a body portion and a surplus fabric top portion merging with the upper end of the body portion and in extension thereof, said body and top portions being woven in one piece and having all edges finished to prevent unravelling, a plurality of rows of slots woven in said surplus fabric top portion as a part of the pattern, one of said rows of slots being woven adjacent the line of merger of the body and top portions and another adjacent the upper extremity of the top portion, said rows of slots being variously threadable upon a curtain rod to make said curtain ready-to-hang at different length adjustments, said panel curtain as fabricated consisting of two adjoining lace blanks, the pattern of one of said blanks being a reverse replica of the other blank, a removable draw-thread woven between said blanks and secured to the warp threads thereof at spaced intervals to complete the panel curtain, the patterns of said blanks in conjunction and said draw-thread, forming one balanced whole, and said ready-to-hang panel curtain being convertible by merely removing said draw-thread, without injury to, or further wastage of, the fabric, into a matched pair of adjustable ready-to-hang curtains, with all of the edges of each curtain of said matched pair finished to prevent unravelling of the fabric.

LESTER FISCHEL.
